UNITED STATES PATENT OFFICE.

WALTER A. KRENTLER, OF DETROIT, MICHIGAN, ASSIGNOR TO KRENTLER-ARNOLD
HINGE LAST COMPANY, OF DETROIT, MICHIGAN, A CORPORATION OF MICHIGAN.

LAST.

1,094,153.

Specification of Letters Patent. Patented Apr. 21, 1914.

Application filed September 12, 1913. Serial No. 789,450.

To all whom it may concern:

Be it known that I, WALTER A. KRENTLER, a citizen of the United States, and resident of Detroit, county of Wayne, State of Michigan, have invented an Improvement in Lasts, of which the following description, in connection with the accompanying drawings, is a specification, like letters on the drawings representing like parts.

10 The desirability of hinging or jointedly connecting the forepart and heel part of a last has been recognized by the trade, as well as by many inventors for many years, but the adoption of the hinged last has been
15 hampered because of the difficulty of getting great strength at the joint to resist the leveling, heeling and treeing pressures. The jointing devices have always necessitated cutting away so much of the wood as to
20 weaken the last. The progress of shoe manufacture has also brought other requirements forward with more prominence of late years so that it is now considered necessary to have a hinged last provided with a lock
25 which will positively lock the last in extended position, and this has heretofore necessitated still further cutting away of the already frail wood. On the other hand, recent shoe styles have tended toward re-
30 quiring a last having an extremely thin crown of the forepart and cone of the heel part, so that the problem of jointing these lasts has become still more difficult, as the formation of sockets, kerfs or other provi-
35 sion for a lock at these regions of the last has been thereby rendered practically impos-
sible because of its weakening effect on the already thin and weak crown and cone por-
tions.
40 My present invention aims to eliminate all the aforesaid disadvantages of the hinged last, my invention being applied to the well-known "Kant-break" last, one form of which is shown in U. S. Pat. 936,138, Octo-
45 ber 5, 1909, which is a type of knuckle last of 608,006, July 26, 1898. This knuckle-joint type of last has proved to be the strongest and most practical and economical from the last-maker's and shoe-manufacturer's
50 standpoints, but the advancing requirements of the trade have become so exacting as above explained that even these lasts fail to stand up under all conditions. In these lasts the pulling or breaking strain, under
55 the buckling pressure of the leveling ma-

chine, for instance, comes on the wood end-
wise of the knuckle between the pintle of the hinge and the outer end of the knuckle, and as the wood is short in length at this point, and is in a relatively slender and unsupport- 60
ed position, these lasts, under severe strain, are apt to break or at least yield suffi-
ciently to make the joint loose, and the last consequently useless. I have discovered
that this weakness of this knuckle-joint 65
type of last can be overcome, notwithstanding
the lessened amount of wood available
(as above explained) and the greater pres-
sures and more rapid movements now ex-
acted, by extending the same general kind 70
of dowel-like joint-member as in Patent
936,138 above and anchoring the said ex-
tended or prolonged joint-member back in
the body of the heel part at a considerable
distance from the pintle, and forward in the 75
forepart at a considerable distance from said
pintle, so that, instead of the holding strain
being borne mostly at the knuckle and
brought by the pintle on the frail wood of
said knuckle, said knuckle is relieved of said 80
holding strain and is depended upon mostly
for its other great strength-giving and last-
alining features and functions, while the
main holding strain is brought at said two
remote anchor points in the heel-part and 85
forepart respectively, where the wood en-
tirely surrounds or envelops the dowel-like
ends in its circumferentially uncut integrity
and at points where it is thickest and strong-
est and largest in mass or bulk, and hence 90
best adapted to receive said strain. A fur-
ther important advantage of my invention is
that just mentioned, viz., although having
the hinge members extended from the
knuckle in opposite directions far into the 95
solid wood, it leaves the wood largely uncut,
or in other words, provides a minimum of
removal of the wood. The advantage of
this will be apparent by bearing in mind
that necessarily there is only a small and 100
relatively frail amount of wood at the waist
of a last anyway, especially a hinged last,
and any invention which eliminates the ne-
cessity of cutting away this wood, results in
making a correspondingly stronger and 105
longer lived last. Also in the preferred em-
bodiment of my invention, I provide an-
choring members or hinge parts, which
snugly fit the anchor cavities and therefore
maintain the last fully and advantageously 110

solid and also rigid laterally and vertically as far as possible. This construction likewise enables me to locate the lock at the hinge region and thereby avoid the necessity 5 of cutting into or bringing any strain upon the thin upper portions of the last at the crown of the forepart and cone of the heel part.

I consider one of the most important features 10 of the present invention to be the combination with the above explained arrangement of the automatic locking mechanism within the space occupied by said extended members and at the knuckle, whereby the 15 last when in extended position is automatically locked with sufficient strength to resist the many collapsing pressures and strains applied during the process of shoe manufacture thereon, particularly during the heeling 20 and leveling machine operations and yet the knuckle is not weakened nor any of the wood cut into or removed. This automatic locking feature, while affording a strong and rigid locking of the last in extended 25 position, nevertheless is so devised as to permit the last to be readily flexed by hand for insertion in or removal from a shoe, and preferably this automatic locking feature also is effective to lock the last in either 30 flexed or extended position, preferably with greater locking force when in the latter than when in flexed position. Furthermore, a subordinate advantage is that I so arrange the automatic locking devices that they are 35 entirely concealed from view, affording no exposed portions on which the shoe upper or lining may catch. The locking devices are contained within the same sockets which are cut or bored for the hinge members; 40 this feature is of particular importance in enabling my improved last to be economically manufactured and assembled, as well as in affording a strong construction at the knuckle. The locking devices are formed to 45 exert their locking tension directly upon the metallic members constituting the hinge and do not bear on the wood of either forepart or heel part, such a wooden bearing being 50 objectionable as it quickly wears and eventually becomes loose and so weakens the locking effect.

In the preferred form of my invention as herein illustrated, I provide in the forepart and heel part a simple bored socket, extending directly into the center of the wood of each part, where the wood is tough, most massive or thickest and most solid, such bores being made in line with each other and with the pivot point in the knuckle on 55 which the two parts are to be swung. I then provide a tubular hinged member which will snugly fill the socket bored therefor and which will extend from one part, preferably the forepart, into the socket in the 60 knuckle of the other part, *i. e.* the heel part,

to a sufficient extent so that it will tend to take up any side or torsional strains and prevent all tendency of one last-part to shift sidewise relatively to the other last-part. That portion of the heel part into which 70 the tubular member extends is cut away sufficiently to permit the flexing as hereinafter described. The forward portion of the tubular member also is slotted to receive the co-operating hinge member which extends into 75 a socket provided therefor in the heel part. The extreme opposite end portions of each member are pinned or riveted to their respective parts, such fastening going through the solid wood of the last remote from the 80 edge or face of either part. I then provide a pivotal hinge for the two members, which also preferably has a bearing in the wood of one part concentric of the knuckle. In the tubular member I provide a coiled spring 85 which may conveniently bear upon the fastening pin or rivet holding said tubular member to its respective part, *i. e.*, the forepart and so form the outwardly extending end of the other hinge member, that said spring may lock the same either in straightened or flexed position. By this construction, the pivot pin on which the two parts of the last are flexed, although it does go through a part of the wood of one part, *i. e.*, 90 lengthwise of the knuckle, is, nevertheless, relieved entirely of the longitudinal strain thereon, which I have explained above has heretofore tended to break out the wood of the knuckle and thereby spring the last, because of the rivets or fastenings through the 95 remote opposite end parts of each hinge member which has a bearing in the most solid and thickest portions of the wood. Furthermore, both the hinge members are 100 concealed from view and the locking devices are also concealed and have bearings only on the metallic parts constituting the hinge and its securing means.

Referring to the drawings, illustrating 110 the preferred embodiment of my invention, Figure 1 is a side view of my improved last with a portion of the wood of both forepart and heel part broken away to show the hinge, which is shown partly in cross section; Fig. 2 is a fragmentary plan view, showing that portion of the forepart and heel part in cross section in which the hinge members are secured; and Fig. 3 is a fragmentary side view, partly in cross section, 115 of the last in flexed position.

In the illustrative embodiment of my invention I have utilized that type of last known in the trade as the "Kant-break" last, although the invention is obviously applicable 125 to other types and forms of knuckle joint lasts. The forepart 1 and heel part 2 are of usual external contour, having a knuckle portion 3 formed on the heel part and fitting into a corresponding concave socket or 130

recess 4 on the forepart, together with a shoulder or vertical bearing face 5 on the heel part, with a coöperating bearing face 6 on an extension of the forepart, this being a feature of the socalled "Kant-break" last. In the forepart I bore a socket 7, lengthwise of the wood-mass and perpendicularly from the pin or pinte at the pivot point on which the two parts are adapted to be flexed which pivot is concentric with the knuckle member 3 and the coöperating recess 4, into the central part of the wood of the forepart, and a corresponding socket 8 into the heel part 2 and similarly located therein. Where this bore cuts the knuckle 3 I cut away a portion thereof as indicated at 9, but of a width corresponding to the width of the tubular dowel member 10, to permit said tubular member 10 which is fitted into the socket 7 to swing during the flexing of the last while at the same time hugging against the sides of the cut as shown best in Fig. 2. The tubular member 10 is formed with a slot 11 in which the coöperating dowel member 12 of the hinge is fitted. The hinge member 12 extends into the socket 8 in the heel part and receives a pin or rivet 13 therethrough, which passes through the solid thick wood of the heel part, and the tubular member 10 receives a corresponding fastening member 14 passing therethrough and fitting within and through the solid thick wood portion of the forepart. The overlapping portions of the hinge members 10 and 12 are suitably bored to receive the pivot pin 15 on which the two parts are flexed, which pivot pin is set through the wood or knuckle 3 concentric with the outer face of said knuckle and with the corresponding face 4 of the forepart, so as to insure smooth, yet snug, tight, turning of the knuckle 3 in the socket cavity 4, as clearly shown in Figs. 1 and 3.

The forward portion of the hinge member 12 is provided with an extension beyond the pivot pin 15, which presents a concave face 16 and a second face 17, each meeting at a point 18, said faces being preferably hardened, or the entire member 12 may be of hardened steel. Within the tubular member 10 is fitted an expansible coiled spring 19, which bears on the fastening 14 and is adapted to exert considerable tension through a hardened steel member 20 upon the projecting portion constituting the faces 17 and 18 of the coöperating hinge member 12. Preferably the member 20 is a ball also of hardened steel, and its size fits that of the concave face 16 to afford a strong locking bearing when the last is in extended position, as shown in Fig. 1. The spring 19 forcing the member 20 into firm engagement with the forward portion of the hinge member 12 will require considerable power to permit the member 12 to be flexed and

the ball 20 to be forced beyond the point 18 and permit it to rest on the face 17. In either position with the member 20 in contact with the concave face 16, or resting on the face 17, the last is locked in position. Furthermore, as the last is flexed and as soon as the member 20, (when said member is a ball or the like,) is forced sufficiently beyond the point 18 and begins to traverse either face 17 or 16, the spring 19 will automatically complete the flexing or straightening of the last and will similarly seat the last in either straightened position, as shown in Fig. 1, or in flexed position as shown in Fig. 3.

It will be noted that the wood of both forepart and heel part is cut away to a minimum extent, and furthermore that the hinge members practically fill up the wood so cut away particularly the tubular member 10, and that portion of the hinge member 12 within its socket which is free of the member 10 may also be tubular if desired. I prefer to employ a headed bolt for the fastening member 13, and may also form the pins 13 and 14 as taper or wedge members, thus further forcing the forepart and heel part 2 into close contact around the knuckle 3 in assembling the last. The fastenings 13 and 14 being through the solid uncut wood part of the last at the thickest portions thereof and remote from the abutting faces 3 and 4 effectually prevent the loosening of the hinge at said abutting faces and thus always retain the two parts of the last in firm, close, and unremitting contact, while permitting the same to be readily flexed. The automatic locking devices are entirely concealed within the tubular member 10 and the spring 19 being seated upon the fastening 14, has a firm metallic bearing which is fitted as a part of the hinge construction and therefore furnishes a bearing for said hinge without special work. The crown 21 of the forepart may be fined down and even concaved as required by recent extreme styles without interfering with or weakening the hinge or locking members in any way whatever, and the entire exterior contour of the wooden portions of both forepart and heel part may be varied to the greatest extent desired without interfering with the hinge construction which is seated in the central portions of the two wooden parts. Coupled with this, and with the strong knuckle-joint combination already explained, the automatic locking feature of the two dowel members also has its bearing and wearing portions upon metal, preferably hardened steel, and there is therefore nothing to wear loose in my improved construction, and both lock and hinge are always maintained in their initial efficiency. The manufacture of the last is simple and the entire arrangement permits an easy and

expeditious assembling of the last and hinged parts. But by far the most important function of my invention is the strength and stability which it gives to the hinged last. 5 My invention makes the knuckle-joint last almost as strong as the block last and makes it possible to continue the use of the hinged last, with all its well-recognized advantages, notwithstanding the multiplying exactions 10 of the modern styles, leveling pressures and other requirements of modern rapid shoe manufacturing, as already explained. I make no claim to the knuckle joint alone 15 nor to the dowel hinge alone nor to the plunger locking device alone, as each of these has existed before, but not in the combination nor with the advantages and results which distinguish my invention. Dowel hinges have always heretofore been 20 used in the general type of last known as the Tyler hinged last (whose general lines of cut are typified in Patents 601,622; 607,978; and 661,397, in which the pintle or pivot point is located at the apex of the V- 25 gap or meeting point where the secant line from the bottom intersects the two secant lines from the top of the last), and have been subject to the fatal weakness inherent in all lasts of this Tyler type, viz. that the 30 leveling pressures and twisting movements of the forepart with relation to the heel-part have brought a shearing strain directly on the hinge at the pintle, so that they could not stand up to the severe usage of the more 35 modern factory-practice. One recognized advantage of the dowel hinge has been that it leaves the wood largely uncut or integral and avoids the necessity of making a plane of cleavage or tendency to split the last 40 apart as when the last is sawed to receive a plate hinge (whether set horizontally as in the Tyler last or vertically as in Patent 608,006 already mentioned), but in the only instance known to me which reached a commercial point (661,397 above) it was necessary 45 to employ two widely spaced apart dowels in order to maintain the joint of the last-parts at the bottom level or alined and to resist twisting tendency. The only instance 50 known to me in the prior art where it has been proposed to employ a single dowel-hinge is shown in Patent 642,341, in which it was attempted to overcome the tendency to twist by making the dowel 8-shaped in 55 cross-section, set with its greatest diameter extending vertically in the last, but it was found in practice that there was still a fatal tendency of the last-parts to twist on each other and also that there was a tendency 60 to split. The increasing exactions as to strength to resist the shearing strains above mentioned and the twisting strains, also above mentioned, were met satisfactorily for several years by the knuckle-joint last 65 already explained hereinbefore, in which the

semi-cylindrical projection or knuckle of wood secures a strong supporting resistance by its engagement with its bed or socket throughout the entire width of the last whereby both the shearing strain is effectually resisted and also the tendency of the last-parts to twist on each other, but, as I have explained in the earlier part of this specification, the still greater exactions of the still more advanced shoe factory practice 70 finally proved too much for this last as then made (Pat. 936,138, being the most advanced example on the market), as the last-joint or connection would give or yield sufficiently to permit the knuckle to loosen in 75 its socket and hence allow the forepart to separate slightly from the heel-part, causing an unevenness on the bottom and sides and a liability of the bottom to gap open slightly and thereby become liable to pinch 80 the lining and crease or cut the leather. My present invention, therefore, combines the great strength of the knuckle joint and its elimination of the shearing-strain and twisting-strain weaknesses with the great 85 strength and anti-splitting advantages and simplicity of the dowel hinge, with the marked result that the hinged last is again rendered capable of meeting the latest factory requirements. Viewed from another 90 standpoint, the main feature of my invention may be stated to reside in preserving all the advantages of the Kantbreak last while removing its weakness by taking practically 95 all the strains which previously existed between the pintle and the knuckle (which previously had to endure all the lengthwise-pull strain of the leveler) away from this point and transferring said strains to the thickest heaviest portions of the forepart 100 and heel-part by employing a jointed dowel hinge and anchoring its opposite ends as far away from the knuckle as the last construction will permit. Thus I have succeeded in bringing together in a single compact construction the great strength resulting 105 from leaving the wood uncut transversely by using a dowel hinge (reaching its maximum of strength in the single dowel), the great self-aligning and vertical-strain-sustaining features of the knuckle-joint construction, and the transference to the thickest heaviest wood-mass of the fore-part and the heel-part of the points of resistance to 110 lengthwise pull and strain under the leveling-machine. At the same time I have eliminated the tendency to shear off and twist which has always heretofore existed in connection with the attempt to use a dowel hinge, the tendency of the pintle to 115 break out endwise the cross-grain wood of the knuckle in the Kantbreak last, and the tendency to split along the planes of the saw kerfs which is present in the remaining 120 forms of hinged lasts which necessitate the 125 130

presence of saw kerfs. And finally I have so combined all these features of construction and advantage that, without cutting the wood or changing the dowel or otherwise complicating the structures, the last is made self-locking in both its lengthened and shortened positions by the self-contained and self-adjusting spring lock. This form of lock is not new in and of itself (being shown in Patent 721,717), but only as applied to my particular construction of hinge and relation of last-parts.

My invention will be more particularly defined in the following claims, taken in connection with the foregoing description and differentiation from the state of the prior art.

Having described my invention, what I claim as new and desire to secure by Letters Patent is:

1. A hinged last having its forepart and heel-part fitted to each other with a knuckle joint, combined with a dowel-like hinge connection consisting of at least two dowel members pivoted to swing intermediate its length in the knuckle and anchored remote from said pintle at its opposite ends within the solid portions of the forepart and heel-part respectively.

2. A last, having a forepart, a heel-part, a portion of the wood of one part extending about the pintle on which said parts swing, and a hinge having a pintle on which said parts swing and having opposite dowel portions extending lengthwise of the last within said forepart and heel-part respectively and anchored adjacent their opposite ends in the body of the respective last-parts.

3. A last, having a forepart, a heel-part, a knuckle extending widthwise of the last on one of said parts and the other part containing a complemental concave socket in which said knuckle fits and turns, said knuckle having a radius sufficiently small to have a substantially semi-cylindrical engagement with the socket, whereby a maximum of resistance to vertical and twisting strains is afforded, each last-part having a longitudinal hole bored therein from said knuckle, and a hinge connection consisting of two dowels pivotally connected by a pintle concentric of said knuckle and extending thence in opposite directions within said two holes and anchored transversely of the last at the ends of the respective dowels within said respective last-parts.

4. A last, having a forepart, a heel-part, a knuckle extending widthwise of the last on one of said parts and the other part containing a complemental concave socket in which said knuckle fits and turns, said knuckle having a radius sufficiently small to have a substantially semi-cylindrical engagement with the socket, whereby a maximum of resistance to vertical and twisting

strains is afforded, each last-part having a longitudinal hole bored therein from said knuckle, and a hinge connection consisting of two dowels pivotally connected by a pintle concentric of said knuckle and extending thence in opposite directions within said two holes and anchored transversely of the last at the ends of the respective dowels within said respective last-parts at the points of approximately greatest wood-mass and strength of said last-parts.

5. A last, having a forepart, a heel-part, a knuckle extending widthwise of the last on one of said parts and the other part containing a complemental concave socket in which said knuckle fits and turns, said knuckle having a radius sufficiently small to have a substantially semi-cylindrical engagement with the socket, whereby a maximum of resistance to vertical and twisting strains is afforded, each last-part having a longitudinal hole bored therein from said knuckle, and a hinge connection consisting of two dowels pivotally connected by a pintle extending approximately the width of the last concentric of said knuckle and extending thence in opposite directions within said two holes and anchored transversely of the last at the ends of the respective dowels within said respective last-parts.

6. A last, having a forepart, a heel-part, a knuckle extending widthwise of the last on one part and the other part containing a complemental concave socket in which said knuckle fits and turns, said last-parts containing holes extending lengthwise of the last in opposite directions from said knuckle and socket at approximately the widthwise middle of the last, and a hinge connection consisting of a dowel-like member occupying the hole in the forepart, a second dowel-like member occupying the hole in the heel-part, said two members mutually overlapping at their meeting ends in the knuckle, a pintle mounted within the knuckle concentrically thereof and passing through said overlapping ends as a center of pivotal movement thereof, a transverse pin extending transversely of the forepart through the forward end of the first mentioned member at the point of approximately greatest thickness and strength of wood-mass of said forepart, and a second transverse pin extending transversely through the heel-part and through the rear end of the second mentioned member at the point of approximately greatest thickness and strength of wood-mass of said heel-part, one of said dowel-like members being tubular to fit its hole, the knuckle having a transverse recess corresponding in width to the diameter of said tube, for preventing widthwise shifting of one last-part on the other last-part.

7. A last, having a forepart, a heel-part, a knuckle extending widthwise of the last

on one part and the other part containing a complementary concave socket in which said knuckle fits and turns, said last-parts containing holes extending lengthwise of the 5 last in opposite directions from said knuckle and socket at approximately the widthwise middle of the last, and a hinge connection and lock consisting of a dowel-like member occupying the hole in the forepart, a second 10 dowel-like member occupying the hole in the heel-part, said two members mutually overlapping at their meeting ends in the knuckle, a pintle mounted within the knuckle concentrically thereof and passing 15 through said overlapping ends as a center of pivotal movement thereof, a transverse pin extending transversely of the forepart through the forward end of the first mentioned member at the point of approximately greatest thickness and strength of 20 wood-mass of said forepart, a second transverse pin extending transversely through the heel-part and through the rear end of the second mentioned member at the point

of approximately greatest thickness and 25 strength of wood-mass of said heel-part, one of said dowel-like members being tubular to fit its hole, the knuckle having a transverse recess corresponding in width to the diameter of said tube, for preventing widthwise 30 shifting of one last-part on the other last-part, a coiled spring held under compression within said tubular dowel against the said transverse pin thereof, and a ball supported loosely by the opposite end of said spring within said tubular member, the adjacent end of the other dowel member having opposite oblique locking seats for said ball to occupy when the last is in fully lengthened position and fully shortened position respectively.

of

In testimony whereof, I have signed my name to this specification, in the presence of two subscribing witnesses.
